UNITED STATES PATENT OFFICE.

LUTHER BECKWITH WOOD, OF OMAHA, NEBRASKA.

LANTERN.

SPECIFICATION forming part of Letters Patent No. 355,240, dated December 28, 1886.

Application filed June 15, 1886. Serial No. 205,925. (No model.)

To all whom it may concern:

Be it known that I, LUTHER BECKWITH Wood, a citizen of the United States, residing at Omaha, in the county of Douglas and 5 State of Nebraska, have invented certain new and useful Improvements in Lanterns; and I hereby declare the following to be a full, clear, and exact description of the same.

My present invention relates to the form of 10 lantern for which Letters Patent of the United States, No. 316,425, were granted to me on the 21st day of April, 1885.

The construction I desire to cover in the 15 present application is identical with that shown and described in my said Letters Patent, except as to the heat-chambers in the tubes, which I now omit, since the device without them operates more satisfactorily, and affords, as I have discovered by experiment since applying for my aforesaid Letters Patent, a 20 decided improvement upon the device shown and described therein, owing to the tendency of the chambers to accumulate gas and produce explosion, which not only destroys the 25 lantern, but is liable to entail disastrous consequences.

In the accompanying drawings, Figure 1 is 30 a sectional elevation of my improved lantern; Fig. 2, a side elevation of a portion of the same, showing details; Fig. 3, a sectional plan view taken on the line 3 3 of Fig. 1; and Fig. 4 a plan view of the burner and oil cup or reservoir of the lantern.

The frame A, globe B, ventilating or draft 35 top C, and oil cup or reservoir D, with the base D', may be of the usual or of any improved construction.

It is the object of my present device, as of 40 my said device already patented, to provide a lantern with means whereby the freezing of the oil in cold weather and smoking of the lantern-globe shall be prevented. These means comprise tubes E, two in number, of equal or substantially equal diameter throughout, and 45 bent toward their lower extremities to afford long arms e and shorter arms e'. The tubes E are fitted in the top d of the oil-cup D in a manner to cause the lower bent portions to lie within the oil-cup and extend nearly to the 50 bottom of the same, thus presenting a comparatively large surface for contact with the

oil. The shorter arms, e', of the tubes E project a short distance beyond the upper surface of the top d, through the latter in line with the wick-tubes f and on opposite sides of the 55 same, and are provided with short pipes or tubes b, bent, as shown, toward their upper extremities and provided with flaring mouths c, to extend above the wick-tubes. The longer arms, e, extend vertically through the globe 60 B to or into the draft-top C, and thereby serve as chimneys to create the draft necessary to draw the heat from the flame at the wick-tubes through the tubes b down and up through the tubes E, and thereby heat the contents of the 65 oil-cup.

The tubes b are not rigid in their positions upon the projecting ends of the shorter arms, e', of the tubes E, but are adjusted in any suitable manner (by simply seating them as shown, 70 if desired) to permit the flaring mouths c to be turned toward and from the flame, and thus permit the temperature of the oil to be regulated by controlling the degree of heat introduced through the oil-cup. 75

The heating of the oil renders its combustion perfect to an extent that tends to prevent smoke, and thus the globe B is kept clear.

I am aware of a lamp provided with a bent tube, the bent portion being within the oil-chamber and the short arm of the tube having a bell-mouth extending over the wick-tube. I am also aware of a lantern constructed with a 80 perforated chamber below its oil-chamber, and with an oil-reservoir in its upper end, the oil-reservoir being connected with the oil-chamber by a tube or duct. The oil-reservoir of this lantern has a central opening, over which extends an inverted funnel connected by a 85 pipe extending through the reservoir with the 90 perforated chamber. I claim neither of the foregoing constructions as of my invention.

What I claim as new, and desire to secure by Letters Patent, is—

1. In a lantern having its oil-cup at the base 95 of the lantern and a draft-top, the combination, with the oil-cup and draft-top, of continuous tubes E, bent to form arms e, extending to the upper part of the lantern adjacent to the draft-top, and shorter arms, e', extending 100 through the top of the oil-cup, the bent portions of the tubes being within the oil-cup,

and tubes *b*, bent toward their upper extremities to extend toward the wick, and provided with flaring mouths *c*, to extend above the wick, as shown, substantially as and for the 5 purpose set forth.

2. In a lantern having its oil-cup at the base of the lantern and a draft-top, the combination, with the oil-cup and draft-top, of bent tubes *E*, having long arms, *e*, extending to the 10 upper part of the lantern adjacent to the draft-top, and shorter arms, *e'*, extending through the top of the oil-cup adjacent to the wick, the

bent portions of the tubes being within the oil-cup, and tubes *b*, bent toward their upper extremities to extend normally toward the 15 wick, and provided with flaring mouths *c*, to extend above the wick, as shown, and adjustably secured upon the projecting ends of the shorter arms, *e'*, substantially as and for the purpose set forth.

LUTHER BECKWITH WOOD.

In presence of—

S. M. BEERY,

W. H. DYRENFORTH.
